UNITED STATES PATENT OFFICE.

ARNOLD REUSS, OF OSHKOSH, WISCONSIN, ASSIGNOR TO LEACH COMPANY, OF OSHKOSH, WISCONSIN, A CORPORATION OF WISCONSIN.

CONCRETE MIXER.

Application filed November 2, 1927. Serial No. 230,466.

This invention relates to concrete mixers and devices of similar nature, and it has among its objects the provision of an improved splash shield for such mixers arranged to prevent splashing of the contents of the mixing drum during the mixing operation that is characterized by a number of features effective in increasing the efficiency and the usefulness of the mixer.

10 The objects of the invention will be best understood from the following description of exemplifications thereof, reference being had to the accompanying drawings, wherein

Fig. 1 is a side elevational view of a concrete mixer embodying the invention, a part of the mixing drum and associated structure being shown in section;

Fig. 2 is an end elevational view of the mixer from the loading side; and

Fig. 3 is a fragmentary sectional view through a mixing drum and a portion of the associated supporting and loading mechanism illustrating a modification of the invention.

25 Referring to Figs. 1 and 2, there is shown a concrete mixer of the type described in the copending application of Elbert C. Leach, Serial No. 124,360, filed July 23, 1926, and assigned to the Leach Company. The mixer comprises a chassis 10 upon which is rotatably mounted a mixing drum 11. The drum is arranged for rotational movement around a substantially horizontal axis and consists of a main cylindrical central portion and 30 two head sections 12, 13 enclosing the two ends thereof. Each of the two head sections is provided with a central aperture 14 and 15, that on the left of Fig. 1 serving as a loading opening for the drum, and 35 that on the right as a discharge opening. The drum is arranged to be suitably rotated by means of a ring gear 16 that is driven from a suitable mechanism carried by the chassis.

40 In front of the loading opening 14 of the drum there is mounted on two upright posts 21 of a frame structure supported on the chassis a loading skip 22 provided with two skip arms 23 pivoted to journaling brackets 24 carried by the posts 21. The dry materials, such as concrete and gravel, that are to be mixed are loaded into the skip 22 and

the skip is then raised by means of a cable 25 arranged to be wound upon winding drums 26 carried by the frame so as to bring 55 the skip into vertical position in which the material from the skip will slide into the interior of the drum through the loading opening 14 thereof. The mixer carries also a water tank 27 from which a measured 60 quantity of water is supplied to the mixing drum through the conduit 28 so that the dry materials and the water may be thoroughly mixed in the drum by rotating 65 the same, as is familiar in the art.

The prior art mixers of the kind under consideration were greatly deficient in that the wet concrete mixed in the drum would splash through the openings 14 and 15 over the neighborhood of the machine, being a 70 source of annoyance to the workers handling the machine, requiring repeated cleaning and resulting in consequent loss of time, and generally cutting down the efficiency of 75 the mixer.

In accordance with the present invention the deficiencies due to splashing through the openings of the mixing drum are avoided by providing splash shields over the drum openings characterized by a number of novel 80 features greatly increasing the efficiency of the machine and simplifying the operations thereof.

In the drawing there is shown back of the loading opening 14 within the mixing drum a splash shield 31 in the form of a substantially circular iron plate. The splash shield 31 extends over substantially the entire loading opening 14, only the upper portion of the shield being cut off to permit entrance of 85 the water conduit 28 into the interior of the drum. As seen in the drawing, the shield 31 is disposed substantially in the plane of the re-entrant end plane, the head 12 being, however, somewhat in front thereof so that 90 when particles of wet concrete drip down from the top portion of the drum they are thrown toward the interior thereof back of 95 the splash shield.

According to the invention, the splash shield does not rotate with the drum but is stationary and is so supported in the interior of the drum as to prevent rubbing thereof against the inside of the drum during the 100

rotation of the latter. A channel iron 33 on the upper side of the frame structure has secured thereto a pair of supporting bars 34 constituting a horseshoe-like U-shaped member, the two lower ends of the two bars carrying hinge pins 35 on which are mounted hinges 36 disposed on the upper edge of the splash shield. The two supporting bars 34 have downward extensions 37 constituting stop bars to prevent the shield 31 to swing forwardly beyond the vertical plane in which it is shown. In this way contact between the edges or any other portions of the shield 31 with the adjacent portions of the mixing drum is absolutely excluded, and thus friction of the parts during rotation of the drum eliminated. In the arrangement shown in the drawing there is also provided an additional stop for the splash shield in the form of a U-shaped member 38 secured to a channel iron 39 constituting the frame of the chassis 10, the upper side of the member 38 projecting through the loading opening 14 into the interior of the drum to limit forward movement of the lower edge of the splash shield 31.

With the foregoing arrangement the splash shield is free to swing around the hinge connection 35 into the interior of the mixing drum 11 to permit loading of the rough materials by means of the skip 22, and, according to my invention, there is provided an automatic arrangement whereby the splash shield is automatically swung inwardly into the drum whenever the skip is raised to load the same. This is effected in a very simple way by providing on the two skip bars 23 two upstanding push arms 41 arranged to be brought against the front of the splash shield 31 and swing the latter into the interior of the drum whenever the skip has been pivoted towards the top around its pivotal connection 24. In order to preserve the front side of the splash shield 31 against excessive wear by reason of the action of the push arms 41, the splash shield carries at its front side two wearing bars 42 so arranged that the upper ends of the push arms 41 shall slide thereover while the latter engage the splash shield in opening the same into the interior of the drum.

With the foregoing arrangement it is not necessary to have separate control for the splash shield, but the same will automatically open the loading opening of the drum whenever the raw material is to be charged into the same, the splash shield swinging away from the opening whenever the skip is lifted. Thus, whenever the skip has been raised to the charging position, the push arms will automatically swing the splash shield away from the loading opening and allow a free flow of material from the charging skip into the drum. The arrangement as described above has an additional ad-

vantage by reason of the fact that during the charging of the dry aggregate the shield is in inclined position towards the center of the drum, as shown by dotted lines in Fig. 1. By reason of this arrangement the shield will deflect the material which is being carried over toward the center of the drum, permitting faster charging. Heretofore the efficiency of the mixers has been greatly cut down because of the fact that as the dry material leaves the charging skip it is not carried away fast enough from the charging opening, thus reducing the speed of the operation of the machine. With the splash shield arranged as shown, a portion of the material is deflected from the charging opening. The material which tends to flow rather rapidly from the charging skip is permitted entrance into the drum, thus avoiding blocking of the drum entrance and securing fast charging without spilling or slopping out of the drum opening.

The arrangement of the stop bars is also very important for the satisfactory operation inasmuch as the splashing of the material in the drum during the mixing period tends to cause the shield to swing outwardly. This might cause damage to the machine and wear out the drum and the splash shield. The stop bars avoid such damage.

In Fig. 3 is shown a modification of the invention in which the skip arms 23 have a positive connection with the splash shield 31 by means of a link 45, one end of which is pivoted to a suitable bracket 46 on the splash shield and the other end of which is pivoted to an arm 47 extending from the skip arms. With this arrangement the position of the shield 31 is at all times determined by the position of the skip. When the skip is in downward position, the shield is held over the loading opening and prevents splashing of the materials in the interior of the drum. There is no necessity for special stop bars because the position of the splash shield is definitely fixed to the link connection. When the skip is raised the splash shield is swung inwardly through the arm 47 and link 45 permitting loading of the dry aggregate drum.

The invention is not limited to the particular details of construction or to the particular type of machine illustrated and described hereinabove, and many other modifications thereof will suggest themselves to those skilled in the art. For instance, it may be applied to drums mounted in other positions than the drum of the mixer shown in the drawing, and it may be used in conjunction with drums in which the mixing is effected by a continuous rotational movement or only partial rotational movement or intermittent rotational swinging movement. It is, accordingly, desired that the appended claims be given a broad construc-

tion commensurate with the scope of the invention within the art.

I claim:

1. A machine of the class described, a supporting frame, a mixing vessel arranged for movement on said frame, said vessel having an opening, a splash shield supported in front of said opening to prevent splashing of the contents of the vessel during mixing operations, means for charging the vessel arranged movably between a charging position in which the contents thereof tend to flow into the vessel and a loaded position in which the contents thereof do not tend to flow into the vessel, and means for causing said splash shield to open the opening of said vessel to permit flow of the charge into said vessel whenever said charging means is brought into the charging position.

2. In a machine of the class described, a supporting frame, a mixing vessel arranged to move on said frame for mixing the contents thereof, said vessel having an opening to the interior thereof, a conduit for guiding the contents of the vessel between the exterior and the interior thereof, a splash shield supported by said frame over said opening to prevent splashing of the contents thereof during mixing operation, said conduit being movable on said frame between a position where it extends into said opening to guide the flow of material therethrough and a position away from said opening, and means for causing said shield to automatically open and close, respectively, said shield opening in response to positioning said conduit in said opening and away therefrom.

3. In a concrete mixer, a supporting frame, a cylindrical mixing drum arranged for rotational movement around a substantially horizontal axis, said drum having an opening at one end thereof, a splash shield supported by said frame in front of said opening, a conduit for guiding the mixing aggregate through said opening between the interior and exterior of the drum, said conduit being movable on said frame between an operative and inoperative position, and means for causing said shield to open and close, respectively, said shield opening in response to bringing said conduit to the operative and inoperative positions, respectively.

4. In a concrete mixer, a supporting frame, a mixing drum mounted thereon for rotation around a substantially horizontal axis, said drum having an opening at one end thereof, a splash shield mounted within said drum in front of said opening, a stationary support for said splash shield, said splash shield being arranged to move inwardly into the interior of said drum to open said opening, and means for limiting the outward move-

ment of said splash shield to prevent contact thereof with the portions of said drum while obstructing the opening thereof.

5. In a concrete mixer, a supporting frame, a mixing drum mounted on said frame for rotation around a substantially horizontal axis, said drum having a central opening at one end thereof, a splash shield mounted within said drum in front of said opening, a support extending from said frame for hingedly holding said splash shield within said drum, said splash shield being movable on said support to permit swinging of the lower edge thereof into the interior of the drum to deflect the contents of the drum to the center thereof, a skip supported on said frame for movement between an operative position in which it communicates through said opening with the interior of the drum and an inoperative position in which it is disconnected from the interior of the drum, and a connection between said skip and said splash shield for swinging the latter open in response to bringing the skip to the operative position.

6. In a concrete mixer, a supporting frame, a mixing drum having an opening, a skip supported on said frame in front of said opening, a hoist for hoisting said skip to an operative position in which it communicates with said drum through said opening and to lower it to an inoperative position out of communication with said drum, a splash shield mounted in front of said opening to prevent splashing of the contents of the drum during the mixing operation, and a connection between the skip and said splash shield to cause opening and closure thereof in response to hoisting said skip and lowering said skip, respectively.

7. In a concrete mixer, a supporting frame, a substantially cylindrical drum mounted on said frame for rotation around its axis in substantially horizontal position, said drum having a re-entrant portion provided with an opening at one end thereof, a splash shield mounted in front of said opening to remain stationary during the rotation of the drum, said splash shield having a pivotal supporting connection permitting swinging of the lower ends thereof into the interior of the drum to cause deflection of its contents towards the center thereof, and means for stopping outward swinging movement of said splash shield during rotation of said drum to prevent contact between the splash shield and the drum.

8. In a concrete mixer, a supporting frame, a mixing drum having an opening, a skip supported on said frame in front of said opening, a hoist for hoisting said skip to an operative position in which it communicates with said drum through said opening and to lower it to an inoperative position out of communication with said

drum, said drum being arranged for rotation about its axis disposed in a substantially horizontal direction, a splash shield pivotally mounted on said support in the interior of said drum in front of said opening and arranged to remain stationary with respect to said drum, and a connection be-

tween the skip and said splash shield to cause opening and closure thereof in response to hoisting said skip and lowering said skip, 10 respectively.

In testimony whereof I have hereunto subscribed my name.

ARNOLD REUSS.
